UNITED STATES PATENT OFFICE.

EMMETT E. HALL, OF LINCOLN, NEBRASKA.

COLLAR-BUTTON.

1,278,337.

Specification of Letters Patent. Patented Sept. 10, 1918.

Application filed March 15, 1917. Serial No. 155,038.

To all whom it may concern:

Be it known that I, EMMETT E. HALL, a citizen of the United States, residing at Lincoln, in the county of Lancaster and State 5 of Nebraska, have invented certain new and useful Improvements in Collar-Buttons, of which the following is a specification.

This invention relates to collar buttons and more particularly to the class of buttons 10 designated as shirt studs generally employed for the purpose of attaching collars to the neck-band of a shirt.

The primary object of the invention is to construct a collar button or shirt stud that 15 will be as immovable after being dropped as it is possible to construct the same, and still retain the essential features necessary to its proper use, so that the button will not roll when dropped upon the floor and thus be 20 temporarily lost as is often the case with the common type of button now generally used.

One of the objects is to provide means for causing the head of the collar button to be at all times in engagement with whatever 25 object upon which it is placed thereby causing the button to be tilted so that it rests on the edge of its base flange and its head, while the base flange is constructed to prevent the possibility of the button rolling 30 while in this position.

Another object of the invention is to provide notches in the marginal edge of the circular base flange so that the tendency of the button to roll will be obviated while, at 35 the same time, the utility of the flange will be in no way restricted and the button will retain its necessary characteristics for the purpose of properly using the same.

The above and additional objects are 40 accomplished by such means as are illustrated in the preferred embodiment and in the accompanying drawings, wherein like characters denote like or corresponding parts throughout the several views, in which;

45 Figure 1 is a perspective view of the collar button constructed in accordance with my invention.

Fig. 2 is a vertical section through the same.

50 Fig. 3 is a top plan view.

Fig. 4 is a side elevation showing the position which the button will assume when dropped upon the floor or other object.

55 Referring to the drawing, wherein is illustrated the preferred form of my invention,

and in which like numerals of reference indicate corresponding parts throughout the several views, the button is preferably constructed in accordance with the well-known method of stamping the button from suitable thin material to form the base flange 1 having its marginal edge rolled upon itself to provide the bead 2. From the center of the base flange is extended the shank 3 which is provided at its terminal with the rounded 60 head 4 of hollow construction to provide an interior substantially spherical space 5. A suitable weight 6 is mounted in this space and preferably consists of lead, but it will be obvious that any other heavy substance 65 may be employed that can be conveniently mounted in the space 5.

At diametrically opposite points on the base flange 1, I have provided a notch 7 formed by cutting out a portion of the marginal edge of the flange thus providing the points or corners 8 for preventing the flange from rolling when the button is tilted upon its side as shown by Fig. 4 of the drawing.

It is obvious from the construction that 80 the collar button does not lose any of its essential characteristics by reason of this construction, and it may be worn just as comfortably and as effectively as is the common type of button. When in use, however, 85 it is well-known among users that immediately upon dropping to the floor, the ordinary type of collar button or shirt stud will immediately disappear under adjacent furniture. This is due entirely to the rounded 90 construction of the ordinary button which permits it to easily roll. With the notches, however, and the weighted head, as above described, the button will immediately stop in approximately the exact spot on which it 95 is dropped. The weight retains the button in tilted position and the notches in the flange make it practically impossible for the button to roll.

By virtue of the weight in the head, the 100 tendency of the button to bound when dropped upon the floor, is obviated and furthermore, the weight tends to hold the button tilted, but will not prevent it from being set upright upon a stand within convenient 105 reach of the user.

From the foregoing it will be observed that a very simple and durable collar button has been provided, the details of which embody the preferred form. I desire it to be 110

understood, however, that slight changes in the minor details of construction may be made without departing from the spirit of the invention or the scope of the claims hereunto appended.

I claim:

1. A collar button having a base and a head, the said base being notched, and a weight attached to the head for coöperation with the notches to prevent the rolling of the button.

2. A collar button comprising a shank having a flange at one end, and a head at the other, notches formed in the flange, and means to coöperate with the notches for tilting the button whereby the said notches

may coöperate with the said means, for preventing the tendency of the button to roll.

3. A collar button having an irregular base, a shank, and a weighted head formed on the terminal of the shank for holding the button in tilted position when dropped to permit the irregular edge of the base to engage the surface upon which the same is dropped.

In testimony whereof I affix my signature in presence of two witnesses.

EMMETT E. HALL.
